GESELLSCHAFT, OF SIEMENSSTADT, NEAR BERLIN, GERMANY

CIRCUIT ARRANGEMENT FOR PRESELECTORS

Application filed March 2, 1929, Serial No. 343,894, and in Austria April 5, 1928.

In automatic telephone exchanges having a single pre-selecting stage often no signal is provided whereby the calling subscriber is notified that he has been switched through 5 to an impulse repeater or group selector and that he can commence to transmit number impulses. This signal—called exchange signal—is generally not required if the number of group selectors or impulse repeaters be 10 comparatively large, thus preventing having to wait for the selector to finish operating even during the hour of heaviest traffic.

In the case of automatic private branch exchanges or sub-exchanges wherein when an 15 outgoing exchange call is made the subscriber's loop is switched through direct to the main exchange, it would appear desirable to introduce a signal in such exchanges for notifying the subscriber that the preselector or 20 the impulse repeater or group selector has been seized.

As the general introduction of an exchange signal in existing exchanges would entail 25 considerable expense, according to the invention for these subscribers' lines pre-selectors are used which give an audible signal (exchange signal) to the subscriber while the pre-selector is testing and after the speaking loop has been switched through to an impulse 30 repeater or group selector or only after the loop has been switched through to the latter.

In the drawing Fig. 1, there is shown by way of the usual circuit diagram, one method of carrying out the invention.

Fig. 2 shows a modification of Fig. 1 arranged to prevent the application of dial tone to the calling line until an idle trunk is connected with.

When the subscriber T takes down his receiver, the speaking loop to the exchange is closed, thereby the calling relay R at the pre-selector is operated over: earth, winding 1 of the calling relay R, back contact t 7, loop of 40 the subscriber T, back contact t 3, resistance Wi 1, battery, earth. Contact r 11 applies busy potential to the test lead going to the final selector. Contact r 18 closes the energizing circuit for the rotary magnet D over: 45 earth, battery, back contact c 17, front contact 50

r 18, rotary magnet D, relay interrupter RU, earth.

The rotary magnet steps the wipers of the preselector forward until the latter has found a free line to the repeater, whereupon the following circuit is closed for the test relay C: 55 earth, battery, front contact r 14, windings I and II of relay C, switch wiper c, resistance Wi 2, earth.

Contact c 13 connects up the cut-off relay T 60 over the following circuit: earth, front contact c 13, cut-off relay T, battery, earth. Relay T is operated and at its contacts t 3 and t 7 it disconnects the calling relay R from the subscriber's loop. The closing of the contacts c 4 and c 10 switches the speaking loop through to the impulse repeater. Relay R locks itself in parallel with the relay A at the repeater: earth, battery, relay B, wiper b, front contact c 4, subscriber's loop, front contact c 10, wiper a, relay A, earth, and parallel thereto, winding II of relay R, front contact r 8, winding I of relay R, earth. At the same time the contact r 9 connects the exchange signal to the subscriber's loop, and the subscriber receives a rattling or buzzing tone as a signal that he can begin the numerical selection. This signal continues until the subscriber's loop is opened for the first time during dialing.

The windings of relay R are given such a resistance that having regard to the resistance of the subscriber's loop the relay A at the repeater receives sufficient current to be able to operate when shunted by the relay R of the preselector.

The signal can also be connected up in such a manner that the circuit for the buzzer or rattle lead is not closed until the test relay C has been operated as is shown in Fig. 2. In that case the exchange signal is applied to the speaking loop after the closing of the contact c 19, which is operated by the test relay.

What is claimed is:

1. In a subscriber's line switch, a line relay, a switching relay, and a dial tone circuit controlled by said relays jointly.
2. In a subscriber's line switch, a controlling line relay, means for maintaining the

- line relay energized after the switch has operated, and means responsive to the operation of said switch for transmitting dial tone to the subscriber through contacts on said 5 relay.
3. In a telephone system, a subscriber's substation including an impulse sending device thereat, a telephone line extending from said substation, a plurality of trunks, a line 10 switch, means responsive when the receiver is lifted at said substation for operating said switch to interconnect said telephone line and an idle one of said trunks, means in said switch controlled by said first means for applying dial tone to the line, and means responsive to the first impulse transmitted over the line for removing the dial tone.
4. In a telephone system, a subscriber's substation including an impulse sending device 15 thereat, a line extending from said substation, a line switch, a controlling relay in said switch, means responsive when the receiver is lifted at said substation for operating said relay over a circuit including two conductors of said line in series, means responsive to the operation of said relay for completing a locking circuit for the relay including the calling line loop and for applying dial tone to the line, and means responsive to the first impulse transmitted over the line for opening 20 said locking circuit to deenergize said relay whereby the dial tone is removed from the line.
5. In a telephone system, a subscriber's line 25 and a calling device associated therewith, a line switch, a plurality of trunks, means for extending a connection from said line to an idle one of said trunks via said switch, means in the switch effective when a connection has been extended for applying a characteristic tone to the line, and means responsive to the first impulse transmitted by the calling device for removing the tone from the line.
6. In a telephone system, a subscriber's line 30 equipped with a calling device, a line switch, a controlling relay in said switch, a plurality of trunks accessible to said switch, means responsive to the initiation of a call from said line for operating said relay whereby said switch extends the call to an idle one of said trunks, means responsive to the operation of said relay for completing a locking circuit for the relay including the conductors of said line, means responsive to the extension 35 of the call when said relay is operated for applying a characteristic tone to the line, and means responsive to the momentary opening of the line by the calling device for opening said locking circuit to deenergize said 40 relay and remove the tone from the line.
7. In a telephone system, a line switch for extending a connection from a calling line to an idle trunk, a line relay energized when a call is initiated on the line, a cut off relay 45 energized when the call is extended to an idle trunk, means responsive when both said relays are energized for applying a characteristic tone to the line, and means responsive to a momentary interruption of the line for deenergizing said line relay whereby the tone is removed from the line. 50
8. In a non-numerical hunting switch terminating a line and having access to a group of trunks, a line relay, a circuit for initially operating said relay to cause said switch to hunt for and connect with an idle one of said trunks, means for opening said circuit responsive to the trunk being connected with, a holding circuit for maintaining the relay operated after said first circuit is opened, 55 and means controlled by said relay for applying a characteristic tone to the line.
9. In a non-numerical hunting switch terminating a line and having access to a group of trunks, a line relay, a circuit for initially operating said relay to cause the switch to hunt for and connect with an idle one of said trunks, means for opening said circuit responsive to the trunk being connected with, a holding circuit completed responsive to the 60 operation of said relay for maintaining the relay operated after said first circuit is opened, and contacts on said relay for connecting a characteristic tone to the line. 65
10. In a non-numerical hunting switch terminating a line and having access to a group of trunks, a line relay, a circuit for initially operating said relay to cause the switch to hunt for and connect with an idle one of said trunks, means for opening said circuit responsive to the trunk being connected with, a holding circuit including contacts of said relay for maintaining the relay operated after said first circuit is opened, means controlled by said relay for connecting a characteristic tone to the line, and means responsive to a momentary interruption of said holding circuit for deenergizing said relay to disable said holding circuit and to disconnect 70 said tone from the line. 75
11. In a non-numerical hunting switch for connecting a calling line with an idle trunk, a line relay operated over the calling line loop to start the hunting operation of the switch responsive to the initiation of a call, a switching relay operated to connect the line through to a selected trunk and to open the original energizing circuit of the line relay, a locking circuit including the calling line loop and contacts on the line relay for maintaining the line relay operated after its energizing circuit is opened, and contacts on the line relay for connecting a tone to the line. 80
12. In a telephone system, a line, a non-numerical hunting switch for connecting said line with an idle trunk, a line relay and a switching relay for the switch, means responsive to a call on the line for operating said line relay over a circuit including the calling 85 line. 90

line loop and contacts of the switching relay to initiate the hunting operation of the switch, means for operating the switching relay to connect the line through to an idle trunk and to open the circuit of the line relay, a holding circuit including the calling line loop and contacts on the line relay for maintaining the line relay operated independent of said first circuit, and a source of tone connected to said holding circuit.

10 13. In an automatic switch having access to a group of trunks, a double-wound line relay energized initially over a circuit including one winding of the relay and a calling subscriber's line loop, means responsive to the energization of said relay for operating the switch to hunt for and connect with an idle one of said trunks, means responsive to effecting the connection with said trunk for opening the initial energizing circuit of said relay and for completing a holding circuit including the two windings of the relay in series and the calling line loop, and means responsive to a momentary interruption of the calling line loop for disabling said holding circuit for the duration of the connection.

15 In witness whereof, I hereunto subscribe my name this 30th day of January, A. D. 1929.

20 30 , FRIEDRICH LILL.
